UNITED STATES PATENT OFFICE.

FREDERICK E. VAN SLYKE, OF COLUMBUS, OHIO, ASSIGNOR TO THE JEFFREY MANUFACTURING COMPANY, A CORPORATION OF OHIO.

MINING-MACHINE.

1,292,543.

Specification of Letters Patent. Patented Jan. 28, 1919.

Application filed April 29, 1911. Serial No. 624,058.

To all whom it may concern:

Be it known that I, FREDERICK E. VAN SLYKE, a citizen of the United States, residing at Columbus, in the county of Franklin and State of Ohio, have invented certain new and useful Improvements in Mining-Machines, of which the following is a specification, reference being had therein to the accompanying drawing.

This invention relates to mining machines and more particularly to machines of the long wall or side cutting type. Among the more important objects of the invention are ample strength of parts and ability to stand up to the work under the most trying conditions; compactness, that is, minimum over all dimensions; quietness of operation; improved means for effecting the entering cut; and adaptability and efficiency in handling and cutting under a wide range of working conditions. The manner in which the various objects are attained will be readily understood from the following description in connection with the accompanying drawings in which I illustrate the preferred form of the invention.

In the drawings:

Figure 1 is a plan view of the machine with a large part of the top of the frame-work or casing broken away to show the interior mechanism.

Fig. 2 is a side elevation of the same, the cutter chain being shown in section on a vertical plane through the axis of the driving sprocket.

Fig. 3 is an elevation of the front end of the machine.

Figs. 4 and 5 are vertical transverse sections on the lines 4—4 and 5—5, respectively in Fig. 1.

Fig. 6 is a vertical section on the line 6—6 of Fig. 1;

Fig. 7 is a plan view of a ring constituting part of the turn table structure which carries the cutter bar;

Fig. 8 is a vertical section taken on the arcuate line 8—8 of Fig. 1.

Figs. 9, 10, 11 and 12 are diagrammatical views illustrating the manner in which the machine is handled and controlled in operation.

Referring in detail to the construction illustrated, 1 designates a casting which constitutes the bed part of the main frame of the machine. At either side of this bed part are upstanding side plates 2 and 3 on which are secured top plates 4 and 5, the side and top plates being secured to each other in the construction shown by angle plates 6, 6, to which the top and side plates are riveted. On the bottom of the bed part and at either side of the frame are longitudinally extending bottom plates or shoes 7, 8, which are secured to the other frame parts by rivets or other suitable means. These shoes are turned upward somewhat at their front ends to facilitate the movement of the machine over the floor of the mine.

At the rear end of the machine the main frame proper carries a bearing and casing bracket or extension 9. This bracket 9 is formed in two parts, the lower part 9^a being bolted to the upper part 9^b, said parts being flanged to facilitate such bolted connection. The parts 9^a, 9^b form a casing or housing for a worm wheel 10 which is fast on a vertical shaft 11 carried in bearings 12 and 13 on the parts 9^a, and 9^b, respectively, of the bearing extension. The shaft 11 carries at its lower end a sprocket wheel 14, which drives a cutter chain 15 that is mounted and carried in the usual manner on a cutter arm 16.

This cutter arm is designed to swing about the axis of the vertical shaft 11 and is mounted in a peculiar manner. At its inner end the arm 16 is rigidly secured to a casting 17, which I term a turn table. This turn table, which is circular in general outline, is formed to receive an outward extending flange 18 formed on the lower side of the bracket part 9^a. 19 is an annular plate made in two parts which is bolted to the top of the turn table 17 so as to overlie the flange 18 thus securing the turn table to the rigid bracket 9 in such a manner that it is free to swing about a vertical axis and is very firmly supported because of the extremely wide bearing support which is afforded it. The turn table is preferably formed at its lower outer edge with a flange 17^a and the

bearing plate 19 is arranged to extend beyond the body of the turn table 17 about as far as does the flange 17^a, and in this manner a peripheral groove is formed on the 5 outer edge of the turn table which is adapted to receive a rope or cable for the purpose of swinging the turn table and the cutter bar. Stud bolts 20 and 21 having eye heads are mounted in the periphery of the turn table, 10 as shown, and to one or another of these stud bolts the cable can easily be secured.

With the cutter bar mounted in the manner described, it is adapted to be swung 180 degrees or more about the axis of shaft 11, 15 and, as said shaft is mounted on the longitudinal center line of the machine, it is clear that the cutter arm can be made to extend from either side of the machine, thus enabling it to cut in either direction along 20 the face of the coal. To secure the cutter arm in working position, I provide a locking pin 22 and form the bearing and casing bracket 9 with a series of holes 23, 23^a, 23^b adapted to receive this pin. The annular 25 plate 19 is also provided with a series of holes 24, 24^a and 24^b which are spaced farther apart than the holes 23, 23^a, and 23^b, but can be brought into register with the latter holes to receive the lower end of the locking 30 pin 22 when it is inserted through one of the holes in the bracket. When the hole 23 registers with the middle hole 24, the cutter arm 16 is at right angles to the longitudinal axis of the machine while the holes 23^a and 35 24^a, or 23^b and 24^b are made to register with each other by swinging the cutter arm somewhat to the left or to the right of the 90 degree position, and when so swung it can be rigidly secured by inserting the locking 40 pin. The annular plate 19 is provided with a set of holes 25, 25^a, 25^b diametrically opposite the holes 24, 24^a, 24^b so that the cutter arm can be similarly locked in any one of several angular positions in relation to the 45 main frame when the machine is arranged to cut toward the left instead of the right.

The cutter chain of the machine is driven by an electric motor 27 which is disposed within the main frame of the machine with 50 its armature shaft arranged at an oblique angle to the longitudinal center line of the machine. The motor is rigidly secured to the bed of the frame by bolts 28, 28. The motor shaft carries at its rear end a clutch 55 plate 29 which is adapted to be engaged by a clutch part 30 which is slidably mounted upon a shaft 31 mounted in bearings 32, 32 formed in or carried by the upper part 9^b which with the lower part 9^a of the bracket 60 9 forms a casing for the worm wheel 10. A worm 34 is fast on the shaft 31 which holds it in position to mesh with the worm wheel.

Ball thrust bearings 35, 36 are preferably 65 arranged at the ends of the worm 34. 27 is

a hinged cover plate or door which closes an aperture in the top of the gear casing and permits ready access to the worm gearing. A suitable hand lever 38 (Figs. 1 and 2) is provided to shift the clutch element 70 30 into and out of engagement with the element 29.

At the front end of the main frame is arranged a rotary tensioning device in the form of a winding drum 39 which is mounted upon an upright shaft 40. This shaft is secured at its lower end in an aperture 41 in the bed part 1 of the frame, being preferably secured by a key against rotation. At its upper end the shaft 40 extends into 80 an aperture formed in a yoke or bridge casting 42 which is rigidly secured to the main frame, it having upright leg parts 42^a and a transverse horizontal plate part 42^b which forms in effect a continuation of 85 the top plate 5 of the frame. The drum 39 is driven by a large spur gear 43, which turns upon the shaft 40, through an intermediate clutch mechanism.

The clutch mechanism last referred to 90 comprises a series of flat disks 44, 44 which are secured at their outer peripheries against rotation relative to the drum shell, and a series of similar disks 45, 45 which alternate with the disks 44, 44 and are secured 95 against rotation relative to a hub or sleeve 46 which is arranged to turn upon the shaft 40. The hub 46 is formed with a series of apertures in its upper face to receive a corresponding number of pins 47 which are slidably mounted in the web of the gear wheel 43. These pins 47 are secured to a flanged ring 48 which can be lifted to move the pins 47 out of engagement with the apertures in the hub part 46, but when they are in 100 their lowered position they obviously connect the said hub part with the gear wheel 43 so that said hub part will turn with the gear.

The clutch is controlled by exerting downward pressure upon a series of pins 49 which are slidably mounted in the web of the gear wheel 43 and have their lower ends arranged to press against a ring 49^a resting upon the topmost clutch plate 45. These 115 pins 49 are carried by a disk or plate 50 upon the upper side of the gear wheel 43. 51 is a hand wheel which has a screw thread engagement with a sleeve-like extension 39^a of the hub of the winding drum. The hand 120 wheel carries a plurality of depending fingers 51^a, which have their lower hooked ends projecting beneath the flange of the ring 48 so that the latter can be raised by screwing the hand wheel upward. A ball 125 thrust bearing 52 is interposed between the lower side of the hub of the hand wheel 51 and the upper side of the plate 50. By screwing the hand wheel 51 downward it is clear that the clutch disks can be pressed to- 130

gether so that the rotation of the gear 43 will be transmitted to the winding drum 39. At the same time by easing up on the pressure the two sets of clutch disks can be allowed to slip more or less in relation to each other, and by turning the hand wheel to its uppermost position the ring, 48 and clutch pins 47 can be lifted so as to entirely disconnect the winding drum from the gear 43.

10 The winding drum 39 is driven from the motor 27 by means of the following mechanism.

53 is a worm mounted on the front end of the motor shaft and 54 is a worm wheel with which 15 it meshes. This worm wheel is mounted on an upright shaft 55 which is supported in the two part casing 56 which incloses the worm and worm wheel. This inclosing casing is preferably bolted to the adjacent end 20 of the motor frame. The shaft 55 carries a crank arm 57 at its upper end which is connected by means of an adjustable connecting rod 58 with a pair of oscillating plates 59. These plates are mounted to swing about an 25 upright shaft 60 which is fixed at its lower end in the bed plate of the main frame and at its upper end in a bracket 61 which extends rearward from the bridge or yoke 42. 62 is a ratchet wheel rotatably mounted on 30 the shaft 60 between the plates 59, and 63 is a pawl carried by the plates 59. A spring 65 which is connected at one end to a lug on the pawl 63 and at its other end to a lug on the connecting rod 58 serves to hold the pawl 35 in operative engagement with the ratchet wheel.

65 is a pawl mounted on the bracket 61 and is held in positive engagement with the ratchet wheel 62 by a spring 66. The pawl 40 65 serves to prevent retrograde movement of the ratchet wheel.

67, 67 are a pair of arms mounted to swing around the shaft 60, being separated from each other by a cross-bar 68 carried by one of 45 the arms. 69 is an arcuate plate secured at one end to the cross connecting bar 68 and disposed adjacent the periphery of the ratchet wheel 62. This arcuate plate serves to disengage the pawl from the ratchet 50 wheel when said pawl is retracted and prevents its reengagement with the ratchet wheel on its forward or working movement until it passes off the end of the arcuate plate. 70 is a shaft rotatably mounted on 55 the main frame and having its rearward end threaded through a trunnion nut 71 carried by the arms 67, 67. The front end of this shaft is provided with a handle 72 by which it can readily be turned to adjust the arcuate 60 pawl lifting plate to vary the effective stroke of the pawl.

65 The ratchet wheel 62 carries a downwardly extending hub or sleeve to which is secured a spur pinion 73 which meshes with 66 the large spur gear 43 so that the rotation

of the ratchet wheel is transmitted to said spur gear and thence through the clutch mechanism to the winding drum 39.

74 is a cable one end of which is made fast to the winding drum 39. 75 and 76 are guide 70 sheaves mounted at the two front corners respectively of the bed frame, and the cable 74 can be passed over either of these sheaves as it leaves the machine, as may be desired.

To feed the machine along the face of the 75 coal, I prefer in practice to carry the cable around the sheave 75, (when the machine is to cut toward the right) thence around a pulley carried by an anchor in advance of the machine, and thence back to a clevis 77 80 or other suitable connecting device on the end of the machine frame. Such an arrangement as this is shown in Fig. 10. The arrangement of the cable may be varied, however. That is, the clevis 77 may be connected 85 to the frame at 78 or 79, rather than at a point in the middle of the machine. Furthermore, the cable, if desired, can be taken off directly from the winding drum without passing over the guide sheave 75, or it can 90 be taken off and carried around the outside of the guide sheave 76. By taking the cable off in these three different ways and by making the returning end of the cable fast to the frame in any one of three positions, it 95 will be seen that the forward draft upon the machine can be varied to a great extent. I find, in fact, that by selecting a suitable arrangement of the cable and a suitable angular position for the cutter arm in relation to 100 the main frame, the machine can be held up to the face and to its work without the use of posts or other fixed guiding devices. When the machine is thus used without fixed guides it is desirable in most cases to set the 105 cutter arm at an angle of less than 90 degrees to the main frame, and to pass the draft cable from the winding drum over the guide sheave next to the coal face and secure the clevis 77 in its position nearest the said 110 sheave. In Fig. 12 I show one of the several possible arrangements of the cable; the various other arrangements which can be employed will be readily understood without special illustration. It should be noted that 115 this great variety of ways in which the cable can be taken off from the machine so as to vary the line of draft is made possible practically by mounting the winding drum upon a vertical shaft.

A starting box 80 for the motor is secured to the side plate 2 of the frame and it is preferably provided with connections by which the motor can be reversed, so that the cutter chain can be driven in either direction to enable the machine to cut along the face either toward the right or toward the left. The swinging arm 81 of the starting box is connected to a rod 82 which extends forward to the forward end of the ma- 120 125 130

chine where it is provided with a handle 83. This brings both the motor control and the feed control at the front end of the machine where they can be conveniently reached by the machine runner.

In the operation of my improved machine it is first brought to a position adjacent the face of the coal, as shown in Fig. 9, with the cutter bar swung around in line with the longitudinal axis of the machine. The machine frame is then secured by jacks or other means against movement, and the propelling cable is passed around the front side of the guide sheave 75 and thence back along the inner side of the machine around the grooved periphery of the turn table 17 and made fast to the stud bolt 20. The clutch 29, 30 is then thrown in and the motor started. The draft of the cable swings the cutter arm against the face of the coal and the machine runner, by varying the pressure on the disk clutch which drives the winding drum, can vary and control the rate at which the cutter arm is swung through a considerable range. When the cutter arm has been swung through 90 degrees, or less, or more, to the desired angular position in relation to the longitudinal axis of the machine, the motor is stopped, and the locking pin 22 is inserted in the alining holes 23 and 24, or 23^a and 24^a, or 23^b and 24^b. The propelling cable is then disengaged from the stud bolt 20, is carried around the rear side of the guide sheave 75, thence forward and around the pulley 85 secured to an anchor 86, and thence back to the machine frame to be made fast to the clevis 77.

The motor is now started again and the machine advances along the face of the coal. If there is any tendency for the machine to work away from the face, the arrangement of the feed cable can be varied to secure a different line of draft and this, with the angular adjustment of the cutter arm in most, if not all, cases will serve to secure a satisfactory guiding of the machine, without the use of posts or the like. The rate of feed can at any time be varied by turning the handle 72 to adjust the pawl and ratchet device, and this means of control is supplemented by the adjustable friction clutch through which the winding drum is driven.

When the machine is cut toward the left, it will be understood that the cutter bits are reversed and that in making the entering cut the cutter arm is swung in the opposite direction, the propelling cable being carried off the winding drum, around the guide sheave 76, and thence rearward to the turn table where it is made fast to the stud bolt 21 (Fig. 11); and when the entering cut has been made the cable is rearranged in relation to the sheave 76 and stretched along the face of the coal in a manner analogous to that above described in connection with the

operation of the machine when cutting toward the right.

It will now be clear that in the operation of my machine the only rapidly moving gears are the worms 34 and 53, the spur gear 43 and the pinion 73 which meshes with it moving slowly. By reason of this feature, the machine is extremely quiet in operation. This is an important result, because in prior machines with which I am familiar spur and bevel gears have been employed, some of which move at relatively high speeds and make so loud a noise that the machine runner is unable to hear the cracking of the roof and so fails to receive warning of the cave-ins which occur from time to time. I have accomplished the elimination of spur and bevel gears in this machine by driving from both ends of the machine. At the same time, by disposing the motor obliquely in relation to the length of the machine compactness is secured in the highest possible degree both as to the height and width of the machine.

The provision of the friction clutch through which the winding drum is driven and of means whereby the draft cable can be used to swing the cutter arm in making the entering cut, enables the machine runner to readily vary through a wide range the rate at which the cutter arm is swung in, and, as the maximum rate of swing is relatively great, full advantage can be taken of easy cutting conditions.

The provision and arrangement of the winding drum and the cable guide and holding devices I consider highly important. These features make it possible to use the feed cable to swing the cutter arm in either direction to cut either toward the right or toward the left; to suitably apply and vary the lines of the cable stresses on the machine so as to guide it as it advances along the coal; and to accomplish such guiding of the machine when cutting either toward the right or toward the left.

What I claim is:—

1. In a mining machine of the class described, the combination of a main frame adapted to be moved bodily along a coal face while resting upon the mine floor, a feed mechanism at one end of said frame for bodily moving it, said mechanism comprising a winding drum and a cable thereon adapted to be engaged with an outside stationary abutment and to adjustably apply draft at a point in either of several different longitudinal lines of the frame, a cutting mechanism at the other end of the frame comprising a horizontally moving chain and an arm supporting said chain and arranged to swing around an axis positioned in the central longitudinal vertical planes of the frame and adapted to project therefrom laterally on either side and to be adjustably

- positioned at either of several angles to the longitudinal lines of the frame, means for securing said arm rigidly to the frame after adjustment, a motor on the frame between 5 the cutting apparatus and the feed mechanism, an armature shaft extending, on one side of the motor, toward the cutting apparatus and on the other side of the motor toward the feed mechanism, power transmitting devices connecting one end of the armature shaft to the cutting apparatus, and power transmitting devices connecting the other end of the shaft to the feed mechanism. 10
- 15 2. In a mining machine of the class described, the combination of a main frame adapted to move along a coal face while resting on the mine floor, a feed mechanism at one end of said frame comprising a winding drum and a cable secured thereto and adapted to be engaged with an outside stationary abutment, said frame being adapted to have the cable connected thereto at either of several points along transverse lines, a cutting mechanism at the other end of the frame comprising a horizontally moving chain and an arm supporting said chain and arranged to swing around an axis positioned in the central longitudinal vertical planes of the frame and adapted to project therefrom laterally on either side and to be adjustably positioned at either of several angles to the longitudinal lines of the frame, means for securing said arm to the frame after adjustment, cutter driving devices connected to the motor at points on one side thereof, and driving devices for the feeding mechanism connected to the motor on the other side thereof. 25
- 30 3. In a mining machine of the class described, the combination of a main frame adapted to be moved along a coal face while resting bodily on the mine floor, a cutting mechanism at one end of the frame comprising a horizontally moving chain and an arm supporting said chain and arranged to swing around an axis in the central longitudinal vertical planes of the frame and adapted to project laterally therefrom on either side and to be adjustably positioned at either of several angles to the longitudinal lines, means for securing the arm rigidly to the frame after adjustment, feed mechanism at the other end of the frame 35 comprising a drum and a cable secured thereto and adapted to be engaged with an outside stationary abutment, and cable engaging means on the frame adapted to permit the direction of the line of draft to be varied to correspond to the angle of adjustment of the cutting apparatus. 40
- 45 4. In a mining machine, the combination of an elongated substantially rectangular main frame adapted to travel with its side parallel and close to a coal face, a motor on
- the frame having its armature shaft inclined to the longitudinal lines of the frame, a horizontally arranged cutter chain, an arm carrying said chain and mounted at one end of the frame on a vertical axis in the central vertical longitudinal plane of the frame, a worm wheel at said axis for driving the cutter chain, a worm near the side lines of the frame on an axis alined with the armature axis and engaging with said worm wheel, the cutter arm being adapted to move across the vertical lines of the worm, a feed mechanism mounted on the opposite end of the frame for moving the frame and the cutter, a second worm alined with the armature shaft on the other side of the motor, a worm wheel meshing with said worm, a drum, a cable on the drum, and power transmitting devices interposed between the worm wheel and the drum for rotating it and tensioning the cable. 50
- 55 5. In a mining machine, the combination of a main frame, a swinging cutter arm carried by the frame and adapted to be swung into a position approximately at right angles to the longitudinal axis of the main frame to effect an entering cut, a rotary tensioning device mounted on the main frame, a flexible draft member engaging the said tensioning device, and guiding means for the flexible draft member comprising a sheave mounted on the main frame adjacent one side thereof, the aforesaid parts being so related that the flexible draft member is adapted to be extended from the rotary tensioning device around the said guide sheave and thence rearward along the side of the main frame to connect with the cutter arm and effect the swinging thereof, or to be extended from the rotary tensioning device around the said guide sheave and thence forward along the face of the coal to exert a forward propelling draft on the machine. 60
- 65 6. In a mining machine, the combination of a main frame, a swinging cutter arm carried by the frame and adapted to be swung from a position parallel to the longitudinal axis of the frame either toward the right or toward the left into a position at right angles to the longitudinal axis of the frame, a rotary tensioning device mounted on the main frame, a flexible draft member engaging the said tensioning device, and guiding means for the flexible draft member comprising a sheave mounted on the main frame adjacent the right side thereof and a sheave mounted on the main frame adjacent the left side thereof, the aforesaid parts being so related that the flexible draft member is adapted to be extended from the rotary tensioning device around either of the said guide sheaves and thence rearward along the adjacent side of the main frame to connect with the cutter arm and effect the swinging thereof in either direction, or to be extended 70
- 75 75
- 80 85
- 85 90
- 90 95
- 95 100
- 100 105
- 105 110
- 110 115
- 115 120
- 120 125
- 125 130

- from the rotary tensioning device around either of said guide sheaves and thence forward along the face of the coal to exert a forward propelling draft on the machine.
- 5 7. In a long wall mining machine, the combination of a low, narrow, elongated main frame adapted to move endwise along a coal face, an elongated endless chain cutting mechanism projecting horizontally 10 from the main frame and mounted thereon to swing about a vertical axis disposed in the central vertical longitudinal plane of the main frame, a vertical sprocket shaft for driving the cutter chain mounted on 15 the main frame to turn on the aforesaid
- axis of the cutting mechanism, a worm wheel on the sprocket shaft, an electric motor having its rotary driving shaft disposed horizontally in a vertical plane extending obliquely to the longitudinal center line of the main frame and approximately tangentially to the worm wheel, and a worm connected with the said motor shaft and meshing with the worm wheel. 20

In testimony whereof I affix my signature, 25
in presence of two witnesses.
